UNITED STATES PATENT OFFICE

134,072

DESIGN FOR A MINIATURE MANGER

Siegfried Buck, New York, N. Y.

Application July 17, 1942, Serial No. 107,587

Term of patent 3½ years

To all whom it may concern:

Be it known that I, Siegfried Buck, a citizen of Poland, residing at 560 W. 218th Street, New York, in the county of New York and State of New York, have invented a new, original, and ornamental Design for a Miniature Manger, of which the following is a specification, reference being had to the accompanying drawing, forming part thereof.

Fig. 1 is a top plan view in open position,

Fig. 2 is a front elevation and

Fig. 3 is a top plan view in the folded state of a miniature manger showing my new design.

I claim:

The ornamental design for a miniature manger, substantially as shown.

SIEGFRIED BUCK.
